UNITED STATES PATENT OFFICE.

LOUIS A. LEMKE, OF CHICAGO, ILLINOIS, ASSIGNOR TO PATENT NOVELTY COMPANY,
OF CHICAGO, ILLINOIS, A CORPORATION OF ILLINOIS.

DESIGN FOR A WALL-RACK.

52,485.

Specification for Design.

Patented Sept. 24, 1918.

Application filed May 27, 1918. Serial No. 236,962. Term of patent 7 years.

To all whom it may concern:

Be it known that I, LOUIS A. LEMKE, a citizen of the United States, residing at Chicago, in the county of Cook and State of Illinois, have invented a new, original, and ornamental Design for a Wall-Rack, of which the following is a specification, reference being had to the accompanying drawing, forming part thereof.

Figure 1 is a front elevation of the wall-rack, showing my new design.

Fig. 2 is an end elevation of said wall-rack.

I claim:

The new, original and ornamental design for a wall-rack, as shown.

LOUIS A. LEMKE.
